Des. 183,854
Patented Nov. 4, 1958

183,854

MILK CARTON HOLDER

Arthur B. Moody, Pasadena, Tex.

Application November 26, 1956, Serial No. 43,950

Term of patent 7 years

(Cl. D58—26)

Fig. 1 is a perspective view of the top, rear, and one side of a milk carton holder showing my new design;

Fig. 2 is a perspective view of the bottom, front, and the other side thereof; and

Fig. 3 is a horizontal cross-sectional view of the handle taken on the line 3—3 of Fig. 1.

I claim:

The ornamental design for a milk carton holder, as shown.
